[57] CLAIM

The ornamental design for a curling iron, as shown and
described.

DESCRIPTION

FIG. 1 is a front elevational view of a curling iron em-
bodying my new design and depicted in a closed position,
the rear elevational view being the mirror image
thereof;

FIG. 2 is a top plan view thereof;

FIG. 3 is a bottom plan view thereof;

FIG. 4 is a left side elevational view thereof;
FIG. 5 is a right side elevational view thereof; and
FIG. 6 is a perspective view of the design in an open
position.

The broken line showing a power cord is for illustrative
purposes only and forms no part of the claimed design.
